UNITED STATES PATENT OFFICE

2,638,848

HYDRAULIC PUMP AND MOTOR

Edward Harry Johnson, Coventry, England, assignor to The Keelavite Company Limited, Coventry, England, a company of Great Britain

Application February 15, 1951, Serial No. 211,118
In Great Britain February 16, 1950

13 Claims. (Cl. 103—42)

1

This invention relates to hydraulic pumps and motors of the kind in which the parts of the pump and motor which enclose the working chamber or chambers and which move relatively to one another so that the working clearances between them constitute leakage paths for the hydraulic fluid, are enclosed within a casing which is filled with hydraulic fluid and in which the hydraulic fluid is intended to be maintained under pressure for the purpose of reducing the leakage of hydraulic fluid through the working clearances referred to and, in some cases, of reducing the unbalanced thrusts acting on parts of the mechanism of the pump or motor.

One example of such a pump or motor is described in the specification of United States Patent No. 2,483,705.

The invention is particularly but not exclusively applicable to hydraulic motors of the kind usually called sensitive motors, that is to say motors which are required to rotate at a speed closely related to their consumption of hydraulic fluid (i. e. the rate at which hydraulic fluid is permitted to pass through them) and to maintain an exact relationship between speed and fluid consumption down to very low speeds, such motors being used, for example, for training and elevating guns and for similar purposes.

It will be seen that with pumps or motors of the kind referred to as described in United States patent specification No. 2,483,705 having a pressure control valve which maintains the hydraulic pressure within the casing at a value between the inlet and outlet pressures of the pump or motor and preferably midway between these pressures, there will be a greater flow of fluid into the casing than out of the casing through the working clearances during part of each revolution of the motor and a greater flow of fluid out of the casing than into it through the working clearances during another part of each revolution of the motor, according to the proportions of the working clearances which, at different points in the rotation of the motor, are subject respectively to the pressures on the high and low pressure sides of the motor, there being alternate flow into and out of the casing through the pressure control valve. In other words, the fact that the pressure control valve maintains a constant pressure within the casing means that the rate of flow of fluid from the working chamber through the parts of the working clearances subject to high pressure varies with the variations in the length of such part or parts of the working clearances occurring during each revolution of the pump or motor.

2

Moreover, similar changes in the rate of flow through the working clearances with variations in the lengths of the parts of the working clearances subject respectively to high pressure and low pressure would occur in other types of hydraulic pumps or motors of the kind referred to having a pressure control valve maintaining a pressure in the casing between the pressures on the high and low pressure sides of the pump or motor.

At high motor speeds when the quantity of fluid flowing through the motor is high the variations in the rate of escape of fluid through the part or parts of the working clearances subject to the pressure in the high pressure part or parts of the working chamber or chambers have little effect since the maximum rate of escape is only a very small proportion of the total flow through the motor. When, however, the rate of flow through the motor is small it will be seen that the variations in the rate of escape of fluid through the part or parts of the working clearances subject to the pressure in the high pressure part or parts of the working chamber or chambers will have an appreciable effect and in fact that, if the rate of flow through the motor is reduced to a point at which it approximately equals the rate of escape of fluid through the part or parts of the working clearances subject to high pressure at the rotational position of maximum escape the motor will come to a stop at this position.

The object of the present invention is to overcome this difficulty and to provide a pump or motor in which the speed of rotation will be closely allied to the rate of fluid flow through the pump or motor over the whole working range including especially the low speed and flow range.

To this end a hydraulic pump or motor of the kind referred to according to the present invention, instead of having a pressure control valve such as is employed in the form of pump or motor described in the specification of United States Patent No. 2,483,705, has a closed casing which is connected at a point displaced from its highest point by a pressure operated non-return valve, permitting flow into the casing from the high pressure side of the pump or motor, and is also connected at approximately its highest point by a second pressure operated non-return valve, permitting flow from the casing, to the low pressure side of the pump or motor.

The non-return valves would be so constructed and arranged that the sum of the pressures necessary to open both non-return valves to cause

flow of fluid into the casing from the high pressure side of the pump or motor and out of the casing to the low pressure side would be greater than the normal steady load working pressure for which the pump or motor is intended, but preferably less than the maximum pressure which the pump or motor and the apparatus with which it is to be used is designed to withstand so that the valves will act together as safety valves preventing the occurrence of dangerous hydraulic loads on the pump or motor or its associated apparatus.

Moreover, it will generally be preferred to provide non-return valves constructed and arranged so that they will open under peak pressure conditions in the apparatus with which the pump or motor is associated and in fact at a pressure appreciably below the peak pressure which would occur during working of the apparatus were the non-return valves not provided so that a periodic opening of the valves and consequent flow of fluid through the casing will be caused automatically at intervals during operation of the apparatus.

When as will often be the case, the pump or motor is intended to operate in either direction and/or to act alternatively as a pump or motor, the non-return valves are preferably duplicated so as to provide a pair of non-return valves arranged to function in the desired manner irrespective of the direction of operation of the pump or motor or of whether it is at the moment serving the purpose of a pump or motor. Thus in such an arrangement there would be provided two pressure operated non-return valves disposed respectively between the interior of the casing and the inlet and outlet ports of the pump or motor so as to permit flow of fluid under pressure from such ports into the casing and two further pressure operated non-return valves arranged respectively between the interior of the casing and the inlet and outlet ports to permit flow of fluid out of the casing. In each case the construction and arrangement of the non-return valves would be such that the sum of the pressures required to cause opening of a non-return valve permitting flow of fluid from one of the ports into the casing and opening of the associated non-return valve permitting flow of fluid out of the casing to the other port exceeds the difference between the pressures in the two ports during the normal steady load working conditions with the pump or motor operating in the appropriate direction.

It will be understood in this connection that the pressure difference required to cause the two appropriate non-return valves to open when one port is at the higher pressure may be the same as or different from that required to cause opening of the other two non-return valves when the other port is at the higher pressure.

The invention may be applied to pumps and motors of the kind referred to of various kinds but one arrangement according to the invention applied to a rotary pump or motor of the so-called rotary abutment type is shown by way of example in the accompanying drawings, in which

Figure 1 is a sectional side elevation of the pump or motor,

Figure 2 is a cross sectional view of the pump or motor in the plane indicated by the line 2--2 in Figure 1,

Figure 3 is a sectional plan on an enlarged scale showing the arrangement of non-return valves provided in the pump or motor shown in Figures 1 and 2, and

Figure 4 is a diagrammatic illustration of a hydraulic system incorporating a pump or motor according to the invention.

In the construction of pump or motor shown in Figures 1, 2 and 3, the pump or motor is of known general type comprising a fluid-tight casing A within which are mounted the parts of the pump or motor enclosing the working chamber. These parts comprise an outer part or housing B having formed therein two intersecting cylindrical bores B¹, B² constituting respectively the outer circumferential wall C of an annular working chamber C¹ and the principal part D of the circumferential wall of a rotary abutment chamber. Secured to one end of the housing part B is an inner part E which forms one end wall C² of the working chamber C¹, the inner circumferential wall C² of the working chamber and the smaller part D¹ of the circumferential wall of the abutment chamber. Secured to the other end of the housing part B is an end plate F which closes the adjacent end of the abutment chamber D, D¹ and has an aperture therein coaxial with and of the same diameter as the outer circumferential wall C of the working chamber, while a ring F¹ coaxial with and of the same external diameter as the inner circumferential wall C² of the working chamber is also secured to the housing B so that there is an annular slot between the parts F and F¹ of the same cross sectional dimensions as the working chamber.

Carried in bearings G and G¹ in the parts E and F is a rotor assembly comprising a shaft H to which is keyed a rotor H¹ comprising a disc-like portion H² from which extends a cylindrical flange-like part H³ which lies within and makes a close sealing fit with the inner and outer circumferential walls of the annular slot between the parts F and F¹ and itself carries two blades H⁴ which extend across the working chamber and make a sealing fit with its inner and outer circumferential walls C, C² and the end wall C¹. The shaft H extends through a fluid-tight gland H⁵ in the casing A.

Mounted within the abutment chamber is a rotary abutment J having two blade-receiving recesses J¹ therein, this abutment being mounted on a shaft J² supported in bearings J³, J⁴ in the part E and driven, so as to rotate at the same speed as but in the opposite direction from the rotor H¹ through gearing K.

Inlet and outlet ports L, M opening into the working chamber, respectively on the two sides 55 of the abutment J communicate respectively with inlet and outlet passages L¹ and M¹. Assuming the device to be in operation as a pump, as the rotor and abutment rotate the fluid is drawn from one of the passages L¹ or M¹ by the blades and 60 delivered through the other and the abutment, while maintaining a seal at all times across the working chamber between the inlet and outlet ports, comes into position for one of its blade receiving recesses J¹ to receive a blade and permit such blade to pass the abutment at the appropriate times.

Pressure balancing recesses and passages are shown associated with the abutment but since these and the general functioning of devices of the kind shown are known they will not be further described.

Mounted on the housing part B is a valve housing N containing two parallel bores one of which comprises a central section O of relatively small diameter opening by way of conical valve seatings

O^1, O^2 into end portions O^3, O^4 of relatively large diameter while the other, P , is of approximately the same diameter throughout its length apart from such small differences in diameter as will be apparent from Figure 3 of the drawings. The ends of the bores O, O^3, O^4 and P are closed by screwthreaded caps Q .

Communicating with the central part O of the bore O, O^3, O^4 is one end of a passage R the other end of which communicates with the interior of the casing A at its highest point as shown in Figure 1. Similarly communicating with the central portion of the bore P is one end of a passage S the other end of which communicates with the interior of the casing A at a point displaced from its highest point. One pair of adjacent ends of the two bores O, O^3, O^4 and P communicate with a common passage T opening into the passage L^1 while the other pair of adjacent ends of such bores communicate with a passage U opening into the passage M^1 .

Associated with each of the valve seatings O^1 and O^2 is a ball valve V, V^1 normally maintained in contact with its seating by a spring V^2 acting through a thrust member V^3 .

Mounted in the bore P on opposite sides of the passage S are two valve seating members W, W^1 making fluid-tight joints with the surface of the bore, these valve seating members being provided with bores W^2, W^3 terminating in valve seatings at their adjacent ends in contact with which ball valves W^4, W^5 are normally maintained by a spring W^6 acting through thrust members W^7 .

It will thus be seen that if the pressure in the passage L^1 or the passage M^1 rises sufficiently relatively to the pressure in the casing A the valve W^5 or W^4 as the case may be will be lifted by pressure transmitted through the passage T or U so that fluid will flow into the casing A through the passage S . Also if the pressure in the casing A rises sufficiently relatively to that in one or other of the passages L^1 or M^1 due to such delivery of fluid into the casing A , one or other of the valves V or V^1 will open, that is to say whichever of these valves leads to the passage T or U for the time being at lower pressure.

In practice the casing A is filled with working fluid and it will be seen that, assuming that there is no air space in the casing A , the pressure in one or other of the passages L^1 or M^1 must rise sufficiently to cause opening of the appropriate valve W^5 or W^4 and of the associated valve V or V^1 before the valves in question will open to permit simultaneous flow of fluid to the casing A through one of the valves W^5 or W^4 and from the casing through the appropriate one of the valves V or V^1 . It will moreover be apparent that the opening of the two appropriate valves and the corresponding flow of fluid into the casing A through the passage S and out of the casing through the passage R will take place whenever the pressure in either of the passages L^1 or M^1 exceeds that in the other by an appropriate amount.

The pressure difference required to cause opening of the valves W^5 and V may or may not be the same as that required to cause opening of the valves W^4 and V^1 . Usually, however, the arrangement and setting of the springs V^2, V^3 and W^6 will be such that approximately the same pressure difference causes the appropriate two valves to open, whether the higher pressure is in the passage L^1 or in the passage M^1 . Preferably, moreover the spring W^6 is of such effective strength relative to that of the springs V^2 and V^3 that approximately the same pressure difference

is required across each of the four valves to open it. Thus whenever a pair of valves opens the pressure within the casing A is approximately half way between the pressures in the passages L^1 and M^1 .

The dimensions of the parts and the forces exerted by the springs are preferably so determined in relation to the characteristics of the hydraulic apparatus with which the pump or motor is to be used that while during normal steady load operation the valves remain closed, the appropriate pair of valves will open each time peak working conditions are experienced so that each time such peak working conditions occur, fluid will be caused to flow into the casing through the passage S and out of it through the passage R . In this way not only does the valve apparatus act as a safety valve to prevent the apparatus being subjected to excessive hydraulic loads but should there be any tendency for air to collect in the highest part of the casing A it will be ejected through the passage R . Thus the casing tends to be maintained completely filled with liquid. In this way, as explained earlier, leakage and variations in such leakage through the working clearances between the parts constituting the working chamber tend to be reduced.

One particularly useful application of the invention is to a sensitive pump or motor constituting part of a hydraulic power transmission system for moving intermittently heavy apparatus, for example a gun or gun turret wherein there may be heavy peak loads when starting and stopping the apparatus with periods of normal steady load between them.

One such hydraulic system is shown diagrammatically in Figure 4, in which the system comprises a hydraulic fluid reservoir X from which a suction passage X^1 leads to the inlet passage M^1 of a hydraulic pump having an outer casing A and constructed as shown in Figures 1, 2 and 3. The outlet passage L^1 of this pump leads through a pressure line X^2 to the inlet port of a control valve Y of the known rotary type having a rotary distributing valve member Y^1 controlled by suitable mechanism diagrammatically shown at Y^2 .

The valve Y has on the one hand two alternative pressure outlet passages Y^3, Y^4 leading respectively to the inlet and outlet passages M^1 and L^1 of a hydraulic motor having a casing A and also constructed as shown in Figures 1, 2 and 3, and on the other hand two relief passages Y^5 leading to the reservoir. Since the valve Y will be of well known form and in itself constitutes no part of the present invention it will not be further described or shown.

The hydraulic motor is connected by suitable transmission mechanism to a load indicated at Z having a considerable inertia such for example as a gun or gun turret.

In operation the pump delivers hydraulic fluid continuously from the reservoir X to the control valve Y which in its central or neutral position closes both the passages Y^3 and Y^4 and opens the passage X^2 to the passages Y^5 so that the pump merely circulates fluid freely.

When the valve member Y^1 is moved in one direction or the other from such central position it progressively closes communication between the passage X^2 and the passages Y^5 while opening one or other of the passages Y^3 or Y^4 to the pressure line X^2 and the other of these two passages to one of the relief passages Y^5 . Thus the motor is caused to rotate in one direction or the other according to the direction in which the

member Y^2 has been moved from its central position.

Since the load Z has substantial inertia, the sudden movement of the member Y^1 may cause peak pressures to be built up in the appropriate one of the passages Y^3 or Y^4 before the inertia of the load is overcome and under such conditions the appropriate pair of non-return valves W^4 and V^1 or W^5 and V^2 would open to limit the hydraulic load. Similarly if the control member Y^1 is suddenly moved to stop movement of the load Z the momentum of the load may build up a peak pressure in the appropriate one of the passages Y^3 or Y^4 which is then closed by the valve Y^1 and the other appropriate pair of non-return valves in the motor will open. Moreover, each time this occurs any air in the casing of the pump will be ejected through the passage R . The non-return valves would however be constructed and arranged so that under normal steady load conditions, that is to say when the load Z is being moved at other than approximately maximum acceleration and is not having approximately maximum deceleration imposed upon it the non-return valves will remain closed.

It will be appreciated that, although for convenience the pump has been described as of the kind shown in Figures 1, 2 and 3 it need not necessarily be provided with non-return valve apparatus according to the invention.

What I claim as my invention and desire to secure by Letters Patent is:

1. A rotary hydraulic machine comprising relatively moving parts enclosing a working chamber with working clearances between the relatively moving parts and inlet and outlet passages communicating with the working chamber, a substantially fluid-tight casing enclosing the said relatively moving parts and with which communicate the ends of the working clearances remote from the working chamber, said casing being arranged to be filled with working fluid, and valve apparatus including in combination a pressure operated non-return valve arranged to permit fluid flow from one of the said inlet and outlet passages to the interior of the casing and a second pressure operated non-return valve arranged to permit flow of fluid from the casing to the other of the said inlet and outlet passages.

2. A rotary hydraulic machine comprising relatively moving parts enclosing a working chamber with working clearances between the relatively moving parts and inlet and outlet passages communicating with the working chamber, a substantially fluid-tight casing enclosing said relatively moving parts and with which communicate the ends of the said working clearances remote from the working chamber, said casing being arranged to be filled with working fluid, two pressure operated non-return admission valves arranged to permit flow of fluid into the casing respectively from the inlet and outlet passages, and two pressure operated outlet valves arranged to permit flow of fluid from the casing respectively to the inlet and outlet passages.

3. A rotary hydraulic machine as claimed in claim 1 in which each of the non-return valves is constructed and arranged to open on the occurrence of approximately the same predetermined pressure difference across it whereby both valves open on the occurrence of twice that pressure difference between the pressures respectively in the inlet and outlet passages.

4. A rotary hydraulic machine as claimed in claim 2 in which each of the non-return admis-

sion valves controlling the flow of fluid from one of the said inlet and outlet passages to the casing is constructed and arranged to open at substantially the same pressure difference across it as causes the opening of the associated non-return outlet valve controlling the flow of fluid to the other of said passages.

5. A hydraulic system including at least one hydraulic machine as claimed in claim 1 in which the non-return valves are constructed to open at a pressure which is greater than the pressure imposed thereon when the system is operating under steady load conditions but less than the pressure imposed thereon when the system is operating under peak load conditions.

6. A hydraulic system as claimed in claim 5 in which each of the non-return valves is constructed and arranged to open at substantially the same pressure difference across it as that required to cause the other non-return valve to open.

7. A hydraulic system including at least one hydraulic machine as claimed in claim 2 in which the two non-return valves which are arranged to open to permit flow of fluid through the casing in each direction are constructed to open at a pressure which is greater than the pressure imposed on them when the system is operating under steady load conditions but less than that imposed on them when the system is operating under peak load conditions.

8. A hydraulic system as claimed in claim 7 in which each of the non-return valves is constructed and arranged to open at substantially the same pressure across it as that required to cause each of the other non-return valves to open.

9. A rotary hydraulic machine comprising relatively rotating parts enclosing between them an annular working chamber, one of said parts being stationary and including the outer circumferential wall of the working chamber through which pass inlet and outlet passages at circumferentially spaced points while the other of said parts rotates and constitutes one end wall of the working chamber and carries at least two spaced blades extending across the working chamber, a rotary abutment extending across the working chamber between the inlet and outlet passages and making a substantially fluid-tight seal with the inner and outer walls of the working chamber and having blade receiving recesses therein which during its rotation come into position to receive the blades and permit them to pass the abutment, a substantially fluid-tight casing enclosing the relatively rotatable parts and the rotary abutment and into which open the ends of the working clearances between these parts remote from the working chamber, and valve apparatus including a pressure operated non-return valve arranged to permit flow of fluid from one of the said inlet and outlet passages to the interior of the casing and a second pressure operated non-return valve arranged to permit flow of fluid from the casing to the other of said inlet and outlet ports.

10. A rotary hydraulic machine as claimed in claim 9 in which each of the pressure operated non-return valves is arranged to open on the occurrence of substantially the same pressure difference across it.

11. A rotary hydraulic machine as claimed in claim 9 in which four pressure operated non-return valves are provided, two of said valves being arranged to permit flow of fluid into the

casing respectively from the inlet and outlet passages while the other two are arranged to permit flow of fluid out of the casing respectively to the inlet and outlet passages.

12. A hydraulic system including at least one hydraulic machine as claimed in claim 9 in which the two non-return valves are constructed and arranged to open at a pressure which is greater than the pressure imposed thereon when the system is operating under steady load conditions but less than the pressure imposed thereon when the system is operating under peak load conditions.

13. A hydraulic system as claimed in claim 12 in which the non-return valves are arranged to open at a pressure which is slightly in excess of the maximum which would be built up in the casing, if it were completely closed, under work-

ing conditions due to leakage through the working clearances of the hydraulic machine at the rotational positions of the parts thereof in which the greatest length of working clearance is subject to pressure from within the working chamber.

EDWARD HARRY JOHNSON.
